UNITED STATES PATENT OFFICE.

CHARLES P. LEWIS, OF DEL RIO, TEXAS.

HARROW.

SPECIFICATION forming part of Letters Patent No. 274,347, dated March 20, 1883.

Application filed August 8, 1882. (No model.)

To all whom it may concern:

Be it known that I, CHARLES P. LEWIS, of Del Rio, in the county of Kinney and State of Texas, have invented a new and Improved 5 Harrow, of which the following is a full, clear, and exact description.

My invention relates to improvements in harrows; and it consists in the peculiar construction and arrangement of the parts, as 10 to hereinafter more fully set forth, and pointed out in the claims.

Reference is to be had to the accompanying drawings, forming part of this specification, in which similar letters of reference indicate corresponding parts in both the figures.

Figure 1 is a plan view of my improved harrow; and Fig. 2 is a longitudinal sectional elevation of the same, taken on the line $x-x$ of Fig. 1.

20 The frame consists of the parallel bars a , connected at the front by the pointed section b , and the said front pointed section is provided with harrow-teeth c , of ordinary form.

A little to the rear of the front end is a 25 small rectangular frame, d , arranged transversely of the main frame on the shaft e , mounted in the side bars, a , so as to turn on its axis. This frame carries the drag-hook teeth f , which are to rake up the roots, clods, and other 30 like matters, and hold them so as to be torn apart and pulverized by the rotating teeth g , mounted on a shaft, h , just behind teeth f , so that its teeth work between the hook-teeth, as clearly shown in the drawings. This shaft h 35 is made to revolve by means of the wheels i , with prongs j , located on each end outside of the frame, so that the prongs engage the surface of the ground as the harrow is drawn along it.

Behind the front set of drag and revolving 40 teeth is another similar set, and more may be added, if desired; but practically two sets will probably be the best.

To each shaft e there is a pulley, k , applied, which is connected by a chain, l , to a hand-lever, m , pivoted upon one of the side bars of the frame, so that the operator can at any time raise up and vibrate or shake the teeth f to 45 discharge any matters clogging in them and not freed by the teeth g .

For the construction of the wheels i , I propose to employ two rings of metal, as shown in Fig. 2, of different sizes, and connected to the shaft by spokes n , extending through both rings, to which rings the prongs j may be connected radially, as shown, with nuts o to secure them, so that they can be readily removed, when required, for repairs or renewal. 55

Having thus fully described my invention, I claim as new and desire to secure by Letters 60 Patent—

1. The combination, with the revolving harrow-teeth g and prong-wheels i , of the centrally-hinged vibratory frame d , carrying drag-hook teeth f , constructed and adapted to operate substantially as described. 65

2. The combination, with the harrow-frame a , b , revolving teeth g , prong-wheels i , and vibratory frame d , carrying the hook-teeth f , of the pulley k , chain l , and lever m , substantially as described. 70

CHAS. PATTON LEWIS.
